UNITED STATES PATENT OFFICE

2,690,868

COMPRESSOR VALVE STRUCTURE

Hewitt A. Gehres, Mount Vernon, Ohio, assignor
to Cooper-Bessemer Corporation, Mount Ver-
non, Ohio, a corporation of Ohio

Application January 26, 1950, Serial No. 140,654

1 Claim. (Cl. 230—21)

1

The invention aims primarily to provide a compressor valve structure which will afford relatively large area of flow of the air or gas which is being passed through the compressor, without entailing corresponding increase in the cross sectional size of the valve structure. In accordance with the invention, I utilize valve mechanisms which may be of the plate type ordinarily used in compressors, and which are annular in form. Then the valve mechanisms are assembled in juxtaposed positions, so that their adjacent faces can readily communicate with an air or gas conduit leading to the space between the valve mechanisms, and the aligned interior spaces enclosed by the valve mechanisms are utilized to provide an interior passageway communicating between the remote faces of the valve mechanisms. In this way, air or gas can be conducted "in parallel" through the valve mechanisms, entering either through the space between the valve mechanisms and passing out through a conduit which is in communication with both of the remote faces of the valve mechanisms through the interior passageway above referred to, or vice versa. Such a valve structure may readily be arranged to serve for compressor intake purposes, or for discharge purposes, and affords gaseous flow through the combined areas of the valve mechanisms, and the required cross sectional diameter of the valve structure will be much less as compared to the prior type of compressor valve customarily used. Furthermore, as later more fully set forth, the interior passageway above referred to serves not only as conduit for gaseous medium passing to or from the cylinder space through the valve mechanism which surrounds the passageway, but also affords communication between the cylinder space and a clearance pocket mounted adjacent the valve mechanism, when the clearance pocket is in operation. Thus the aforesaid passageway serves the valve mechanism and the clearance pocket jointly, and wherever such an intake or discharge valve mechanism is located, an accompanying clearance pocket may be readily provided without requiring extensive, space consuming structural alterations of the end portions of the compressor cylinder, where space is at a premium. Further features of the invention will be in part obvious and in part specifically referred to in the description hereinafter contained which, taken in conjunction with the accompanying drawings, discloses certain preferred forms of compressor valve structures which are constructed in accordance with the invention; the disclosure however should be considered merely

2

as illustrative of the invention in its broader aspects. In the drawings—

Fig. 1 is a sectional view taken through a compressor inlet valve structure constructed in accordance with the invention, said valve structure being shown in operative relation to the adjacent parts of the cylinder structure.

Figs. 2 and 3 are sectional views taken respectively on the lines 2—2 and 3—3 of Fig. 1, looking in the direction of the arrows.

Fig. 4 is a view similar to Fig. 1, but showing a valve structure constructed to function as a compressor discharge valve.

Referring first to Figs. 1 to 3, the invention is disclosed as applied to a compressor cylinder 1 having therein an intake conduit 2 which leads into the cylinder head or housing 3, the latter also serving to house the intake valve structure now to be described, and having an intake port 4 through which air or gas will enter the main cylinder space 5 of the compressor, when the intake valve structure is open.

Since the valve structure shown in Fig. 1 comprises two valve mechanisms which are similar in most respects, a description of one will largely serve for the other. The upper valve mechanism shown in Fig. 1 is provided with an annular valve seat member 6, having intake passages 7 and 8 grouped around a central shell 9 which the valve seat member 6 encloses. An annular valve guard member 10, likewise surrounds the central shell 9 and is provided with a series of discharge passages 12, 13 and 14. A plate valve 15 of ring-like form is interposed between the valve seat member 6 and the valve guard member 10, and is urged toward its seating position in which the passageways 7 and 8 are closed, by an appropriate number of helical springs 16 (Figs. 1 and 3) which yieldingly urge the plate valve 15 downwardly as the parts appear in Fig. 1.

A second valve mechanism of similar character to the one just described, likewise encloses the central shell 9 in juxtaposed and inverted relation to the valve mechanism just described, i. e. the valve seat member 6a of this latter valve mechanism faces the valve seat member 6 previously described, and the valve guard member 10a of the second mentioned valve mechanism is located at the face of the latter which is remote from the valve guard member 10. The passages 12, 13 and 14 discharge into a chamber 151 which is at one end of the valve assembly, and the discharge passages 12a, 13a and 14a discharge into a chamber 16 which is at the other end of the

valve assembly, these two chambers 15 and 16 being in communication through a central passageway 17 which extends through the central shell 9.

Likewise the intake passages 7, 8 and 7a, 8a of the two valve mechanisms are both in communication with an annular chamber 18 which surrounds the two mechanisms, the latter being shown as having a spacing collar 19 (Fig. 1) interposed therebetween. The valve assembly is shown as held together by a nut 20 (Fig. 1) at the top of the central shell 9, the chambers 15 and 18 being separated by an annular strut 21 (Fig. 1).

Thus when the piston (not shown) is moving to the left as the parts appear in Fig. 1, the resulting suction lifts the upper plate valve 15 from off its seat and lowers the plate valve 15a from its seat, thus affording flow of the air or the gas to be compressed through intake conduit 2 into chamber 18, then "in parallel" through the two valve mechanisms to the chambers 15 and 16 which are in communication through the central passageway 17, and from thence through the intake port 4 into the cylinder space 5.

I have shown in Fig. 1, a clearance pocket 22 (Fig. 1) which is aligned with the valve structure previously described. When valve 23, which seats upon an opening 24 through the strut member 21, is open, the clearance space 22 is in communication with the cylinder space 5 through the passageway 17 etc. previously described, thus partially unloading the compressor.

In Fig. 4 a valve structure of similar character is shown in a form adapted to serve for discharge purposes from the cylinder space 5 through a discharge port 25 in the cylinder head 3, and then through the valve structure to a discharge conduit 26 in the cylinder. In this form of the invention the upper valve seat member 6b occupies an inverted position with respect to the valve seat member 6 previously described, in such manner that its intake passages 7b and 8b are in communication with a chamber 27 above the valve assembly. The valve guard member 10b of Fig. 4, is disposed underneath the valve seat member 6b, and the plate valve 15b of Fig. 4 is yieldingly pressed upwardly against its seat as shown in Fig. 4. Likewise the lower valve seat member 6c of Fig. 4 occupies an inverted position with respect to the lower valve seat member 6a of Fig. 1, in such manner that the intake passages 7c and 8c thereof are in communication with a chamber 16c at the lower end of the valve assembly, this chamber being in communication with the chamber 27 at the top of the valve assembly, through a central passageway 17a which is enclosed by the central shell 9a of Fig. 4. The valve guard member 10c of the lower valve mechanism in Fig. 4, is likewise inverted in position with respect to the valve member 10a of Fig. 1, and thus the discharge passages 12b, 13b, 14b, and also the discharge passages 12c, 13c and 14c of Fig. 4, are all in communication with the annular chamber 18a which encloses the valve mechanisms. In Fig. 4 the annular strut 21a separates the chambers 16c and 18a, and holds

the valve mechanisms in position, a cap 251 being shown in Fig. 4 as underlying the valve structure to hold the latter in position. Thus when the piston moves to the right in the cylinder space 5, as the parts appear in Fig. 4, the resulting pressure will unseat the plate valve 15b in a downward direction, and unseat the plate valve 15c in an upward direction, whereby the air or gas being delivered from the compressor will flow in part downwardly thru the upper valve mechanism into chamber 18a, and in part thru the central passageway 17a into chamber 16c, and then upwardly thru the lower valve mechanism of Fig. 4, into chamber 18a, and from thence out thru the exhaust conduit 26.

While the invention has been disclosed as carried out by the above described specific forms of compressor valve structure, it should be understood that changes may be made therein without departing from the invention in its broader aspects, within the scope of the appended claim.

I claim:

In combination, a compressor cylinder having cylinder space therein which extends to an end portion thereof, and a compressor valve and clearance pocket structure located at said end portion of said cylinder, said structure including a housing having therein an open ended shell providing a gaseous medium conducting passageway extending through said shell, which passageway is in open communication at the inner end portion thereof with the cylinder space at said end of the compressor, and valve mechanisms surrounding said shell and spaced therealong, said valve mechanisms each having intake and discharge passages disposed exteriorly of said shell and each valve mechanism having valve means interposed between its passages, which valve means is urged toward a position obstructing the flow of gaseous medium through the valve mechanism; said housing having a gaseous medium conducting chamber disposed exteriorly of said shell and which is in communication with the aforesaid passages of one type of each valve mechanism, said passages of the remaining type of said valve mechanisms being respectively in communication with the opposite end portions of said passageway, said housing also having a clearance pocket mounted adjacent the outer end portion of said passageway, and a valve interposed between said clearance pocket and passageway, whereby said passageway serves to connect both the valve mechanisms and the clearance pocket to said cylinder space, when said last mentioned valve is open.
